CUTTING HEAD FOR DRY SHAVERS

Christiaan Jacobus Josephus Dankers, Eindhoven, Netherlands, assignor, by mesne assignments, to Hartford National Bank and Trust Company, Hartford, Conn., as trustee

Application May 3, 1946, Serial No. 667,152
In the Netherlands March 18, 1942

Section 1, Public Law 690, August 8, 1946
Patent expires March 18, 1962

4 Claims. (Cl. 30—43)

1

This invention relates to a cutting head for a dry-shaver. It is characterized by that the part of the cutting plate which is to be laid against the skin comprises two or more concentric paths, each of which is provided with apertures and comprises a separate annular running surface for a cutting member, said concentric paths being relatively separated by one or more circular grooves, while a central depression is provided inside the inner annular path and the apertures in the paths extend into the supporting side-walls of said depression.

A cutting plate is already known in the art which comprises a path provided with slits and an annular running surface, at the inside of which a central depression is provided, the slits extending with their extremities preferably widened into the supporting outer wall as well as into the wall of the central depression. Such a cutting plate has proved to be highly satisfactory in practice.

As compared with this known cutting plate the one according to the invention offers, however, the advantage that, even with equal diameter of the cutting plate, considerably quicker shaving is obtained, since the possibilities of the hairs being caught are considerably greater. When use is made of, for example, two concentric paths, the possibilities of catching hairs will generally be doubled, since with a single stroke of the cutting plate across the skin there is passed in addition in two diametrically opposite points the depression which is concentrically located between the paths and the hairs which are erected inside the depression as a result of the bulging of the skin are supplied in the said points under favorable conditions to the ends of the slits provided in the side-walls of the depression (respectively in the outer wall of the inner path and the inner wall of the outer path).

Relatively to the above-mentioned known cutting plate of equal diameter, the fact that the active shaving surface is reduced by the surface required for the circular depression does not constitute any essential drawback which would neutralise the advantage obtained by the increased hair catching possibility, since with a cutting plate of the known kind it is customary to utilise a quick-rotating cutting member. The width of the annular running surface covered by the cutting member which is either rotating or vibrating about a shaft in a circular path is of more or less minor importance in view of the high speed of the cutting member. In fact, in this case the hairs need pass through a but small length of slit to be cut off.

2

Another advantage of the cutting plate according to the invention consists in that the circular depression between the concentric paths may serve, in addition, as a strengthening groove, while, again as compared with the said known cutting plate of even diameter, the paths for the cutting member owing to their smaller width resulting from the circular depression are less liable to deflection.

10 It is mentioned, however, that it is of course not necessary for the cutting plate according to the invention to be of the same diameter as the said known cutting plate and that it may be larger in diameter in particular when use is made of more than two concentric paths.

15 The apertures in the paths are preferably continuous slits, the two extremities of which extend into the supporting side-walls. As far as the space available permits, these extremities may 20 alternatively be widened to be funnel-shaped, so that the introduction of the hairs is facilitated.

25 Further, corresponding slits in the paths are preferably provided in alignment with each other, due to which alignment the slits may be provided in a simple manner in one operation with the aid of a free milling cutter.

30 The circular depressions between the concentric paths may be interrupted in several suitable points, in such manner that these points serve 35 as rigid connecting bridges between the concentric paths, more particularly when the cutting plate is punched and pressed from thin material.

35 Since this method may, however, involve a loss of active shaving surface (less catching possibilities) it is advisable that the circular depression should constitute a continuous groove. In accordance with the shape chosen, the material and the thickness of material it may be necessary, in order to avoid troublesome deflection, that the 40 bottom and the side-walls of the groove-shaped depression are so strengthened as to constitute a rigid construction, which highly contributes to the rigidness of the whole.

45 The invention will be explained more fully by reference to the accompanying drawing showing, by way of example, a few embodiments thereof.

Fig. 1 shows a top plan view of a cutting plate having shortened slits according to my invention.

50 Fig. 1-a shows a cross-sectional view of the cutting plate of Fig. 1 taken along the line 1a—1a.

Fig. 2 shows a top plan view of a cutting plate with radially extending long slits according to my invention.

55 Fig. 2-a shows a cross-sectional view of the

cutting plate of Fig. 2 taken along the line 2a—2a.

Fig. 3 shows a top plan view of a cutting plate with diagonally extending slits according to my invention.

Fig. 3-a shows a cross-sectional view of the cutting plate of Fig. 3 taken along the line 3a—3a.

Fig. 4 shows a top plan view of the cutting member used with the cutting plates of Figs. 1, 10 2 and 3.

Fig. 4-a is a cross-sectional view of the cutting member of Fig. 4 taken along the line 4a—4a.

Fig. 5 shows a top plan view of a modification of the cutting member of Fig. 4.

Fig. 5-a is a cross-sectional view of the cutting member of Fig. 5 taken along the line 5a—5a.

Fig. 6 is a top plan view of another modification of the cutting member of Fig. 4.

Fig. 1 shows the cutting plate 1 of a dry-shaver of which the portion which is to be laid against the skin comprises two concentric paths 2 and 3, each of which is provided with apertures 4 and comprises a running surface 5 and 6 respectively. The paths 2 and 3 are relatively separated by a circular depression 7, while a central depression 8 is provided inside the inner part 3. The apertures 4 in the paths 2 and 3 extend into the supporting side-walls 9, 10 and 11, 12 respectively. In this example the central depression 8 comprises a bottom 13.

The slits provided in the paths 2 and 3 of Fig. 2 are preferably continuous slits extending from the interior to the exterior, as is indicated by 14, due to which the active shaving surface is increased. The slits 15 provided in the paths 2 and 3 of Fig. 3 are preferably continuous slits diagonally extending from the interior to the exterior of the plate. These slits are provided in both paths in alignment with each other and may consequently be cut in a single operation, for example with the aid of a free milling cutter.

In order to give the cutting plate according to the invention a sufficiently rigid construction, it may be desirable to connect the two paths by means of strengthening ribs or the like. To this end, the annular depression 7 may be interrupted in several points, in Fig. 3 for example at 16. When use is made of a punched cutting plate, it may for example be interrupted at 16. If desired, there may be provided at this place another strengthening rib, shown in the Figure 3 and indicated by 17, which protrudes from the flat portion of the cutting plate which is to be laid against the skin.

However, by making the portion of the depression 7 of a rigid construction, for example by means of sufficiently thick walls and a sufficiently thick bottom at 18, strengthening connections between the paths 2 and 3 are rendered superfluous, so that the depression 7 may be without interruption, which contributes to the shaving capacity. Slits which are widened at their extremities are designated by 19 of Fig. 2.

A suitable cutting member belonging to the cutting plate according to the invention is indicated by 20 in Fig. 4. It comprises a certain number of cutting arms 22 and 23 respectively which project from a plane portion 21 as shown by Fig. 4-a and are located in several concentric paths which are relatively separated. The co-operation between such a cutting member and the cutting plate according to the invention will be clear without further explanation. By means

of two apertures 24 it may be driven by a shaft with lugs or in any other known manner.

Since it is in general difficult to cause the two running surfaces 5 and 6 for the cutting member 5 of Figs. 1, 2 and 3 to be located exactly in the same plane and, in addition, these running surfaces may be chosen in fundamentally different planes, a cutting member as shown in Figs. 5, 5-a and 6 is preferable.

In Fig. 5 use is made of a star 25 of resilient material which has secured a little chisel 26 to the extremity of each of its arms. It is thus possible to obtain an accurate engagement of each chisel with the running surface.

15 In Fig. 6 all the cutting arms 27 and 28 respectively, which are located in concentric paths, are united into separate parts 29 and 30 respectively, each of which mechanically constitutes one unit. The two parts are driven from the central portion 20 by means of two lugs and two recesses 31, the relative possibility of movement between the two parts being such that each can adjust itself on the associated running surface.

What I claim is:

25 1. Dry shaving apparatus, comprising an annular cup-shaped cutting plate and an enclosed resilient cutting member, said cutting plate being provided with a central recess and with at least two substantially flat concentric annular shaped running surfaces for the said cutting member and comprising at least one ring-shaped recessed portion extending between the running surfaces thereof, side walls connecting said annular running surfaces to said central recessed portion and to said ring-shaped recessed portion between the running surfaces, said apertures extending into said side walls, said ring-shaped portion being integral with said cutting plate and extending below the shaving surfaces of the cutting plate, and said cutting member having at least two sets of concentric cutting elements respectively contacting said two concentric running surfaces.

2. Dry shaving apparatus, comprising an annular cup-shaped cutting plate and a cutting member, said cutting plate being provided with a central recessed portion and with at least two substantially flat concentric annular shaped running surfaces for the said cutting member and comprising a plurality of arc-shaped recessed portions extending between the running surfaces of said cutting plate, side walls connecting said annular running surfaces to said central recessed portion and to said arc-shaped recessed portions between the running surfaces, said running surfaces having a plurality of apertures therein, said apertures extending into said side walls, said arc-shaped portions being integral with said cutting plate and extending below the shaving surfaces of the cutting plate, and said cutting member having at least two sets of concentric cutting elements respectively contacting said two concentric running surfaces.

3. Dry shaving apparatus, comprising an annular cup-shaped cutting plate and two concentric annular shaped cutting members, said cutting plate being provided with a central recessed portion and with at least two substantially flat annular concentric running surfaces for the said members and comprising a recessed ring-shaped portion extending between the shaving surfaces thereof, side walls connecting said annular running surfaces to said central recessed portion and to said ring-shaped recessed portion between the running surfaces, said running surfaces having a

plurality of apertures therein, said apertures extending into said side wall, said ring-shaped portion being integral with said cutting plate and extending below the shaving surfaces of the cutting plate, each of said cutting members being provided with cutting arms for one of said surfaces, the outer of said members being driven by the inner member.

4. Dry shaving apparatus, comprising an annular cup-shaped cutting plate and an enclosed cutting member, said cutting plate being provided with a central recessed portion and having at least two substantially flat concentric annular shaped running surfaces for the said cutting member, said cutting plate further comprising a plurality of curved portions, said curved portions being integral with said cutting plate and extending between and below the running surfaces of the cutting plate, side walls connecting said annular running surfaces to said central recessed portion and to said curved portions, said running surfaces having a plurality of apertures therein, said apertures extending into said side walls, the side of

the said cutting plate to be placed against the skin also being provided with a plurality of ridge portions radially extending from the said central recessed portion and being integral with said cutting plate.
